(57) **CLAIM**

The ornamental design for a front portion of a motor vehicle and/or toy replica thereof, as shown and described.

DESCRIPTION

FIG. 1 is a front perspective view of a front portion of a motor vehicle and/or toy replica thereof showing my new design;

FIG. 2 is a rear perspective view thereof;

FIG. 3 is a front view thereof;

FIG. 4 is a rear view thereof;

FIG. 5 is a top view thereof; and,

FIG. 6 is a right side view thereof.

The claimed design is shown darker than the surrounding lighter environmental subject matter, the latter being no part of the claimed design.
